his Attorney.

UNITED STATES PATENT OFFICE.

CLARENCE W. CARTER, OF MINNEAPOLIS, MINNESOTA, ASSIGNOR, BY MESNE ASSIGNMENTS, TO THE DU-ALL MANUFACTURING COMPANY, OF CLEVELAND, OHIO, A CORPORATION OF OHIO.

MOP.

Application filed July 30, 1917. Serial No. 183,403.

To all whom it may concern:

Be it known that I, CLARENCE W. CARTER, a citizen of the United States, residing at Minneapolis, in the county of Hennepin and 5 State of Minnesota, have invented certain new and useful Improvements in Mops, of which the following is a specification.

My invention relates to mops and has for its object to provide a fabric carrying member that can be readily reversed to cause 10 either side thereof to face the floor at will.

In carrying out my invention I provide a fabric carrying member pivotally attached to a handle portion in such a manner that 15 the fabric carrying member can be turned about the pivot sufficiently to cause either side of the fabric to rest upon the floor. My improved mop is particularly adapted for use in connection with the mop head which 20 is the subject matter of my patent numbered 1,209,639, dated December 19, 1916. It is, however, not limited to use in connection with said mop head since it is capable of 25 use with other mop heads.

25 The full objects and advantages of my invention will appear in connection with the detailed description thereof and are particularly pointed out in the claims.

In the drawings illustrating the application of my invention, in one form,—

Fig. 1 is a plan view showing the manner in which the mop head is applied to the carrying member. Fig. 2 is a view illustrating the manner in which the fabric carrying member can be reversed. Fig. 3 is a rear elevational view of the fabric carrying member and its support. Fig. 4 is a side elevation of the same. Fig. 5 is a plan view partly in section showing the mop head completely applied to the carrying member.

Referring to the drawings, 1 represents a handle, the lower end of which is provided with a bearing 2. This bearing is preferably formed in a shank adapted to be secured to the handle. The preferred form of shank consists of two metal half portions 3 and 4 formed from a single piece of material folded together to form the bearing 2 and the two portions secured together with rivets at 5, 6 and 7, which pass through both of the half portions. A hole 8 is provided in the shank to aid in securing the same to the handle. The particular construction of the shank is not

claimed in this application. It is obvious that a bearing similar to the bearing 2 can be formed on the end of the handle in any desired manner.

The fabric carrying member is formed 60 from rod-like material and consists of a curved member 9 terminating in two offset portions 10 and 11 which are connected at their inner ends by a portion 12 which is mounted in the bearing 2, as best shown in Fig. 5. The off-set portions 10 and 11 are of such length as to bring the portion 12 at substantially the center of the curved member 9 and the length of the portion 12 is just sufficient to extend through the bearing 2 without binding upon the ends of the same. As a result of this construction the handle is pivotally attached to the fabric carrying member at substantially the center thereof and said member can be rotated 70 around the bearing 2 through nearly three hundred and sixty degrees, if desired. When the mop is lifted and held in the hand a rotation of one hundred eighty degrees is sufficient to cause the fabric carrying member to be reversed. This member can, however, be readily reversed in the manner shown in Fig. 2 by turning the handle half way over, whereupon a slight end-wise thrust exerted upon the handle 80 will cause said member to turn in bearing 2 and bring the other side of the fabric over upon the floor. In my preferred construction, one of the off-set members, for instance the member 10, is left unattached 85 to the corresponding end of the curved member 9, the latter end being displaced out of the plane of the off-set portions, as best shown in Figs. 3 and 4. A mop head 13, such as that of my patent previously referred to, can be readily mounted on the curved member by inserting the unattached end thereof in the core of said mop head and sliding the same along upon the curved member until the entire mop head is carried thereon. After this has been done I prefer to secure together the disconnected ends of the curved and off-set members, as by welding, in order that the mop fabric 90 may be held firmly in place.

The operation and advantages of my invention will be apparent from the foregoing description. The mop head can be readily reversed in the manner described. No matter which side thereof is facing the floor,

the application of force on the handle is always approximately at the center of the mop head. The mop can be used, if desired, by a person standing in a fixed position and swinging the mop back and forth since the pivotal connection permits the mop fabric to remain flat upon the floor regardless of the inclination of the handle.

I claim:

- 10 1. A mop comprising a mop-fabric supporting frame having a radially disposed U-shaped yoke extending inwardly and terminating substantially at the center of said frame, a handle pivotally connected to the 15 central portion of said yoke and a mop

fabric through which the frame extends centrally thereof whereby the fabric is the same on both sides of the frame.

2. A mop comprising a frame, mop fabric mounted on said frame, a U-shaped yoke extending radially inward from a point in said frame toward the center thereof, and a handle pivotally connected to the central portion of said yoke, the frame extending centrally through the fabric whereby it projects uniformly therefrom in all directions.

In testimony whereof I affix my signature.

CLARENCE W. CARTER.
